WORKHOLDER FOR LENS BLANKS

Otto Gustave Haussmann, Philadelphia, Pa.

Application December 16, 1932, Serial No. 647,659

9 Claims. (Cl. 51—217)

This invention relates to a work holder for lens blanks especially applicable to the manufacture of fused bi-focal and fused multi-focal lenses, in which it is necessary to grind and polish one or more depressions or counter-sinks in the glass blank for the purpose of grinding one or more lenticular facets in the blank into which a glass button of higher refractive index is seated and fused, bringing about in the fused lens blank, a variation of focal powers.

It is customary in the grinding of all ophthalmic lenses to mount the blank on the work holder by means of pitch. It has not been attempted insofar as I am aware to clamp the blanks in the work holder without the use of pitch or other adhesive. The so-called "sticking up" of the lens is attended with certain inherent disadvantages; the pitch must be warmed to the proper consistency, otherwise the blank will fly off while being ground; the pitch is subject to cracking during the grinding operation through any one of a number of causes, and it requires to be immersed in ice water at the end of the grinding operation in order to detach the lens from the pitch. A certain proportion of breakage is expectable as the result of this primitive method of mounting the blanks for grinding.

The present invention has for one of its objects the provision of a work holder comprising a frame for receiving the lens blank, with mechanical means for clamping the blank in said frame.

Another object of the invention is to provide means for mounting the lens holder tiltably, with adjustment for tilt so that the blank can be presented to the grinding lap at different angles, for varying the shapes, sizes and depths of the ground facets. In grinding a multi-focal lens, that is to say, one which has more than two focal fields, a different setting is required for each field. The distant field, the transition field and the reading field can each be ground and polished by a setting of the blank holder which merely requires tilting the lens holder at various angles. Where there are lateral fields, the centers of which are radially displaced, it becomes necessary not only to tilt the lens blank holder, but also to give it a partial rotation and the means for imparting this rotation independent of the position of tilt constitutes a further object of the invention.

Still another object of the invention is the mounting of a plurality of the lens blank holders symmetrically to an axis and providing means

for imparting to them an identical variation of tilt, and providing also means for rotating them through identical arcs irrespective of the position of tilt through means selectively operable.

Other objects of the invention will appear as the following description of a preferred and practical embodiment thereof proceeds.

Referring now to the accompanying drawings which form a part of the following specification and throughout the several figures of which the same characters of reference have been employed to designate identical parts:

Figure 1 is a plan view of the work holder for lens blanks in which three lens blank holders are employed;

Figure 2 is a section taken along the line 2—2 of Figure 1, the work holder being shown in operative relation to a convex grinding lap;

Figure 3 is a section taken along the line 3—3 of Figure 1;

Figure 4 is a section taken along the line 4—4 of Figure 1;

Figure 5 is a section taken along the line 5—5 of Figure 2, viewed from beneath;

Figure 6 is a perspective view of the revoluble element of the lens blank holder; and

Figure 7 is a sectional view through a concave lap showing the employment of the work holder in an inverted position from that shown in Figure 2.

Referring now in detail to the several figures, the numeral 1 represents a base or support having a central hub 2, the hub being provided with a tapered socket 3 adapted in one utilization of the work holder to frictionally embrace the tapered end of a rotating spindle, for rotating the work holder.

It is immaterial insofar as the inventive concept is concerned how many lens blank holders are supported on the base 1, the present illustrative embodiment showing three, each of which is carried by a bracket 4, said brackets being symmetrically arranged and carrying axles 5 in suitable bearing lugs 6. The prolongations of the axes of said axles intersect in the angles of an equilateral triangle, the altitudes of which triangle intersect at a common point in the axis of rotation of the base 1. Each of the lens blank holders comprises a frame 7, preferably circular and having bearing lugs 8 extending from its lower face and journaled upon an axle 5. Thus the frames 7 are tiltably mounted upon said axles. The hub 2 is externally threaded as shown at 9 in Figure 2, and carries a ring nut 10 which travels in and out relatively to said hub when screwed

110

upon the threads 9. The inner portions of the lowerfaces of the frames 7 rest upon said ring nut. The latter may be screwed in any preferred manner, being here shown provided with a plurality of indentations 11, engageable by a suitable pointed tool for turning said nut. The tilting of the frames 7 is accomplished by means of this nut and since all rest upon it, the degree of tilt imparted to each will be the same. A spring 12 normally biases the lens blank holders against the nut 10.

Each of the frames 7 is provided with a revolute lens blank seat 13 comprising a ring, the outer portion of which revolves in a channel in the frames 7. The upper face of the ring 13 is provided with an annular flange 14 within the confines of which the lens blank is seated. The flange 14 is discontinuous through a certain arc as indicated at 15 in Figure 4, the space at 15 receiving the upper limb 16 of a clamping lever 17. Said clamping lever is pivotally mounted in a lug 18 forming part of the frame 7. The lower limb 19 of the lever 17 is provided with a set screw 20 or its equivalent, which abuts against the frame 7 so that by tightening the set screw, the clamping lever 17 is tilted to advance the limb 16 inwardly and downwardly into engagement with the lens blank firmly holding it in position against its seat. By loosening the set screw, the limb 16 is retracted, releasing the lens blank so that the latter can be easily removed.

In imparting rotation to the lens blanks for the purpose of radial displacement of the same for the grinding of the lateral fields or facets, the axles 5 function as shafts, each being provided with a bevelled gear 21 meshing with a complementary bevelled gear 22 carried on a stub shaft 23 journalled in the support 1. The lower portion of said support is provided with an annular channel 24 closed by an annular disk 25 and forming a housing for an annular gear 26. Said annular gear is retained in the same circumferential path by means of a flange 27 on the lower face of said gear seated in a corresponding annular race 28. The interior circumference of the gear 26 is formed with teeth 29 which engage spur gears 30 mounted on the lower portions of the stub shafts 23. The outer circumferential periphery of the gear 26 is provided with worm teeth 31 in mesh with the helices of a worm 32 supported in a suitable off-set of the base or support 1. Said worm has an extending stem 33 with a knurled knob 34 by means of which the worm can be rotated. Thus the annular gear 26 is revolved and through it simultaneous motion is imparted by means of the spur gears 30 to each of the axles 5. The said axles are each provided with a gear 35 meshing with an annular rack 36 formed on the lower face of the ring 14. Thus revolution of the ring 14 is accomplished and with it the radial displacement of the lens blanks.

In view of the fact that the revolutionary movement is imparted about the axes of the axles, said movement is entirely independent of the position of tilt of the several lens blank holders.

In grinding concave facets, the work holder will be positioned as shown in Figure 2, with reference to the grinding lap, the work holder being rotated by means of a spindle, not shown.

In making ordinary fused bi-focal lenses, only one counter-sink is necessary, the depth, size and relative position of which on the lens blank can be accurately determined by a mere setting of the

nut 10 so as to obtain the proper tilt of the lens blank holders. In grinding multi-focal lenses, the distant field, the transition field and the reading field each being symmetrical with respect to the same radius can be ground merely by altering the angle of tilt without requiring radial displacement of the lens blanks. In order to grind the side fields, it becomes necessary to change the relative position of the lenses turning them either to the right or left. This is accomplished by manipulation of the worm 32. The angle of tilt can be read from a scale 37 on the side of one of the frames of the lens blank holder, referred to an index point 38 mounted on one of the bearing lugs 4. The radial displacement of the lens blank seat may be read from a scale 39 formed on the face of the annular gear 26 and visible through a window in the support or base 1, said scale being referred to an index 40 marked on the support 1 adjacent said window.

In grinding convex facets, the work holder is placed in inverted position in the concave face of the grinding lap as shown in Figure 7, and moved about in customary manner by a pointed tool resting in the socket 3.

It will be understood that the embodiment of the inventive principle of my invention as above illustrated and described is merely exemplary, and that the invention is not limited to the employment of three lens blank holders as shown, but may include any desired number of lens blank holders. Neither are the details of construction or the arrangement of parts as shown to be construed as limiting the scope of the invention except to the extent prescribed by the terms of the appended claims.

What I claim is:

1. Work holder for lens blanks comprising a rotary element, a lens blank holder carried eccentrically by said element, means for adjustably tilting said lens blank holder relative to the axis of rotation of said rotary element, and means for revolving a portion of said lens blank holder independent of its angle of tilt.

2. Work holder for lens blanks, comprising a rotary element, a plurality of lens blank holders symmetrically and tiltably carried eccentrically by said element, means for simultaneously adjusting the angle of tilt of said lens blank holders and means for simultaneously revolving an element of each of said lens blank holders independently of their angle of tilt.

3. Work holder for lens blanks as claimed in claim 2, including an axle for each lens blank holder on which the latter is tiltably mounted, each lens blank holder including a revolute lens seating member, and driving means between said axle and said lens seating member.

4. Work holder for lens blanks comprising a hollow rotary base, brackets on said base, an axle in each bracket, said axles being symmetrically arranged with respect to the axis of rotation of said base, lens blank holders each comprising a frame tiltably mounted on one of said axles and a revolute lens seat carried in said frame, means also carried by said frame for clamping a lens blank in said seat, stub shafts mounted in said base associated respectively with said axles, a ring gear in said base, a worm for revolving said ring gear, gearing connecting said ring gear with said stub shafts, gearing connecting said stub shafts with said axle, said lens seats being provided with an annular rack on their lower faces, and gearing between said axles and said racks whereby upon rotation of said ring gear by

- said worm, said lens seats are simultaneously revolved.
5. Work holder for lens blanks as claimed in claim 4 including means for simultaneously tilting the tiltably mounted elements of said lens blank holders.
6. Work holder for lens blanks comprising a rotary element, a plurality of lens blank holders symmetrically and tiltably carried eccentrically by said element, means for simultaneously adjusting the angle of tilt of said lens blank holders, said lens blank holders each including a lens holding element revolvable independently of the angle of tilt of said lens blank holders.
- 10 7. Work holder for lens blanks as claimed in claim 2, including an axle for each lens blank holder on which the latter is tiltably mounted, each lens blank holder including a revolvable lens seating member, a gear connection between said axle and lens seating member, a master gear, a gear connection between said master gear and each of said axles, and means for revolving said master gear.
- 15 8. Work holder for lens blanks comprising a support, a lens blank holder on said support in-
- cluding means forming a seat for the lens blank, said means having an abutment, a clamping element pivoted on said lens blank holder at a point below the plane of said seat and on the opposite side from said abutment comprising a bell crank lever having one arm of such length as to engage the edge of the lens blank, and a screw engaging the opposite arm of said bell crank lever and abutting against said support for rocking the end of said lens blank engaging arm inwardly and downwardly, forcing said blank both against said abutment and against said seat.
- 20 9. Work holder for lens blanks comprising a support, lens blank holders arranged on said support symmetrically about a common axis and tiltably mounted on axes lying in a plane or planes perpendicular to said axis, said lens blank holders being provided with rims adjacent the said axis of symmetry, and clamping levers pivotally mounted at the sides of said lens blank holders remote from said axis of symmetry and having ends adapted to engage lens blanks at points remote from said axis of symmetry in clamping relation to said rims.
